UNITED STATES PATENT OFFICE.

ALFRED W. KNUTSON, OF GALESBURG, ILLINOIS, ASSIGNOR TO ROWE MANUFACTURING CO., OF GALESBURG, ILLINOIS, A CORPORATION OF ILLINOIS.

HOISTING DEVICE FOR ELEVATED CARRIERS.

1,296,814.

Specification of Letters Patent. Patented Mar. 11, 1919.

Application filed November 2, 1917. Serial No. 199,870.

To all whom it may concern:

Be it known that I, ALFRED W. KNUTSON, a citizen of the United States, and a resident of Galesburg, in the county of Knox and 5 State of Illinois, have invented a new and useful Hoisting Device for Elevated Carriers, of which the following is a specification.

My invention relates to chain or cable-10 operated overhead carriers, such as litter carriers, and particularly to means for raising and lowering the receptacle or carrier common in devices of this nature, and it consists, substantially, in the improvements 15 herein disclosed.

One of the objects of the invention is to provide novel take-up devices for a portion of the chain.

Another object is to provide a yielding 20 take-up mechanism.

A still further object is to provide a take-up mechanism which acts also as a brake.

Other objects will presently appear. Some 25 of these are obvious and some particularly pointed out.

In the accompanying drawings, which illustrate a preferred embodiment of the invention:

Figure 1 is a side elevation of a litter 30 carrier partly broken away and partly in section, the receptacle shown in substantially its uppermost position;

Fig. 2, an enlarged perspective detail of 35 parts hereinafter more fully described, partly broken away and partly in section;

Fig. 3, a side elevation of a litter carrier in which are embodied my improvements, the receptacle shown in substantially its lowermost position; and

Fig. 4, an enlarged perspective detail of 40 the chain-guide-shoe or guard-shoe.

Considering the drawings in detail, 2 denotes a suitably supported elevated track upon which roll the wheels 3 of carriages 4.

5 designates an ordinary type of receptacle swung between sustaining-arms 6 each of which is connected to and hung from a chain 7.

8 indicates an endless operating-chain 50 bracing a drive-chain-wheel 9 fixed on a shaft 20 journaled in bearings 12, 12 in spaced pairs of arms 13, 14, respectively, depending from the carriages 4. 15, 15' denote a pair of supporting and guiding 55 plates spaced a slight distance apart and

their ends secured to the arms 13 and 14. 16 designates a split wheel of the combined pin and sprocket type, journaled on an axle 17 mounted in bearings in the plate 15, and 18 designates a like wheel journaled on an axle 60 19 mounted in bearings in said plates. Worms 20 on the shaft 10 engage the pins 21 of said wheels to rotate them in the usual manner. The hereinbefore described parts are fully described in United States Letters 65 Patent No. 1,239,110, granted to me September 4, 1916.

21 denotes a contractile spring disposed between the plates 15, 15' and substantially midlength thereof. The line a—a, Fig. 1, 70 indicates the midlength of said plates. Each end of said spring engages a cross-bar 22 which connects the inner ends of a pair of arms which form a yoke 23. In the relatively outer end of each yoke is rotatably 75 mounted a sheave 24, its axle being designated by 25. Each of these sheaves is preferably formed on its opposed faces with chain-guides 26. The ends of the axle 25 project beyond the yoke members, and on 80 each of these projecting ends is secured a clip 27 which slides on the adjacent plates 15 or 15' as the case may be.

28, 28 denote chain-guide shoes each of 85 which is pivoted, by means of a pin 29 passing through apertures 30 in the ears 31 of the shoe, between the plates 15, 15'. Each shoe has at its inner end a mouth 32 and its forward end constitutes a nose 33 substantially V-shaped in cross-section and substantially concentric with the hub 34 of the sprocket-wheel 16. On each pin 29 is rotatably mounted a sheave 35.

One (which I may term the outer) end of 95 each chain 7 is, as above stated, secured to one of the receptacle-sustaining arms 6. The chain passes thence over and engages the teeth of the sprocket-wheel 16, passing beneath the nose 33, thence through the mouth 32, thence embracing the adjacent 100 sheave 24, thence embracing the sheave 35, and its terminal secured to a cross-bar 37 in the yoke 23. The chain is thus laid in folds, as shown in Fig. 1.

Assume the parts to be in the relative positions shown in Fig. 3. The operator will 105 actuate the chain 8 to thereby impart movement in the proper direction to the drive-wheel 9, shaft 10 and worms 20. The latter will engage the pins 38 on the opposed faces 110

of the spaced cheeks comprising the hoisting-wheels 16 and 18 to thereby rotate them and cause their sprocket-teeth to engage and draw upward the links of the chains 7. In 5 so doing, the operator is assisted by the stored energy of the expanded spring 21 which in contracting to its normal position (Fig. 1) draws upon both yokes 23 and thus upon both chains 7. It is to be observed, 10 therefore, that to this extent at least the act of retrieving or elevating the receptacle 5 is automatic. During the upward progress of the receptacle the spring will, through the instrumentality of the yokes 23 and the pulleys 24 and 35, aided somewhat by the sprocket-teeth 36 and mouth 32, automatically take up a large portion of the chains 7, sufficient, in fact, to prevent any part of the latter from falling into the receptacle 15 6 or being in the way of the operator. The shoes 28 are so located that one of the worms 20 turns freely in the concaved terminal of each.

Now assume the parts to be in the relative 25 positions shown in Fig. 1. To lower the receptacle the operator pulls the chain 8 to operate the wheel 9, shaft 10, worms 20 and wheel 16 in the proper direction. A slight pull will be sufficient, for the weight of the 30 descending parts will cause them to overcome the friction of the chain and the resistance of the spring, the receptacle being thus lowered automatically, simultaneously storing energy in the spring 21. However, 35 the spring resists the gravity-tendency of the receptacle to fall with great speed and the movement of the latter will thus be smooth and even. If it be desired to stop the receptacle at any point intermediate its 40 extremes of motion, the operator may accomplish this by merely stopping the chain 8 or even by placing his hand beneath the receptacle and exerting a slight upward pressure thereon, the spring acting as an equalizing and stabilizing agent.

Hereinafter the receptacle 5 is termed a "load."

I claim as my invention the following, to-wit:

1. In a hoisting-device, a load, a pair of 50 hoisting-chains secured to opposite ends of the load, a spring connecting adjacent ends of said chains, and means for applying power to the chains.

2. In a hoisting-device, a load, a hoisting-chain for raising and lowering it, a sliding sheave for taking up a portion of the chain, and a spring for moving said sheave in one direction.

3. In a hoisting-device, a load, a hoisting-chain for raising and lowering it, a sliding sheave for taking up one of the portions of the chain and a spring for automatically moving said sheave in one direction.

4. In a hoisting-device, a load, a hoisting-chain for raising and lowering it, a sliding take-up, and a spring for automatically moving the take-up in one direction.

5. In a hoisting-device, a load, hoisting-chains each secured at one of its ends thereto, 70 a way, a pair of take-up sheaves slidable in said way, a yielding connection between said sheaves, and means for connecting each of said chains with one of the sheaves.

6. In a hoisting-device, a load, hoisting-chains each secured at one of its ends thereto, 75 a pair of take-up elements, a way in which they slide, means for connecting each of them with the other end of one of said chains, and a spring connecting said take-up 80 elements.

7. In a hoisting-device, a load, a hoisting-chain connected therewith, a sprocket-wheel for driving it, means for driving the sprocket-wheel, a guide-shoe having a nose 85 substantially concentric with the sprocket-wheel and overlying the chain, said shoe having also a mouth through which the chain passes, a slideable sheave over which the chain passes, a non-slideable sheave 90 over which it also passes, and means for securing that end of the chain which is distant from the load.

ALFRED W. KNUTSON.
